Inventor

F. R. Cornwall.

UNITED STATES PATENT OFFICE.

FREDERICK R. CORNWALL, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

PULVERIZER.

1,144,352.

Specification of Letters Patent. Patented June 29, 1915.

Application filed November 30, 1910. Serial No. 594,918.

To all whom it may concern:

Be it known that I, FREDERICK R. CORNWALL, a citizen of the United States, residing at St. Louis, Missouri, have invented 5 a certain new and useful Improvement in Pulverizers, of which the following is a full, clear, and exact description, such as will enable others skilled in the art to which it appertains to make and use the same, 10 reference being had to the accompanying drawings, forming part of this specification, in which,

Figure 1 is a vertical section taken approximately through the center of a pulverizer of my improved construction. Fig. 15 2 is an enlarged vertical section taken on the line 2—2 of Fig. 1. Fig. 3 is a perspective view of an adjacent pair of the disks utilized in my improved pulverizer. Fig. 4 20 is a perspective view of a rotary adjustable sleeve made use of in my improved pulverizer.

This invention relates to a new and useful improvement in pulverizers of that type 25 commercially "known as the "Williams Mills", characterized by pivoted revolving hammers which act upon the material as it enters the machine at the hopper or feed end thereof, crushing said material as it 30 rests upon the bottom of the hopper, or breaker plate, as it is sometimes called, the material being further disintegrated or crushed by the hammers acting thereon as the material is carried over the cage or 35 grinding surface. The crushed material falls through the openings in the cage or grinding surface into a suitable receptacle located beneath the machine.

The hammers or beaters which revolve 40 about the shaft, while made of a material whose resistance to wear is its essential quality, will, in time, wear away at their striking ends, and the farther these striking ends are removed from the breaker plate 45 and grinding surface, the less becomes the capacity of the machine.

It is the purpose of my present invention to provide simple means whereby these revolving hammers or beaters may be adjust- 50 ed outwardly to take up the wear (or inwardly, if occasion requires, as when a new cage is introduced to replace a worn one), said means consisting of a series of disks

fixed on the pulverizer shaft, and a series of disks rotatably arranged on the shaft 55 between the fixed disks, both series of disks being provided with inclined slots through which pass rods upon which the hammers or beaters are pivotally mounted. The slots in one series of disks are oppositely disposed 60 relative to the slots in the opposite set of disks, and thus, when the adjustable set of disks is rotated, the rods which pass through the slots are moved radially relative to the shaft, and the hammers are adjusted in- 65 wardly or outwardly, depending upon the direction of rotation of the adjustable disks.

To the above purposes, my invention consists in certain novel features of construction and arrangement of parts hereinafter 70 more fully described and claimed.

Referring by numerals to the accompanying drawings, 1 indicates the casing of the pulverizer, 2 the breaker plate, 3 the grinding surface or cage, and 4 the cover of the 75 machine which may be hung or mounted upon the casing, as desired.

5 designates the shaft of the pulverizer, upon one end of which is fixed a driving member 6 preferably in the form of a pulley. Loosely mounted upon the shaft 5 is a sleeve 7, which latter is arranged for rotation in suitable bearings 8 formed on the sides of the casing, and one end of said sleeve is provided with a head 9 having a 85 clutch face 10.

Arranged to slide upon a key 11 seated in the shaft 5 adjacent the end of the sleeve provided with a clutch face 10, is a collar 12 provided with a clutch face 13, which opposes said clutch face 10. This collar 12 is normally held in its forward or set position with the clutch face 13 in engagement with the clutch face 10 by means of a wedge key 14 which passes through a suitable 95 aperture formed through the shaft 5, and said wedge key bearing against the outer face of the collar 12.

Rigidly fixed in any suitable manner upon the sleeve 7 is a series of disks 15, and formed therethrough, preferably at equal distances apart, is a series of tangentially disposed slots 16. Interposed between the disks 15 are adjustable disks 17, and seated in the hubs thereof are pins 18 which pass through 105 segmental slots 19 formed in the sleeve 7,

and the central portions of said pins are seated in the shaft 5. The disks 17 are provided with a series of tangentially arranged slots 20, which are oppositely disposed with relation to the slots 16. Passing through the various sets of slots 16 and 20 are rods or bolts 21, and pivotally mounted thereon between the disks 15 and 17 are hammers or beaters 21.

10 The operation of the pulverizer constructed as herein shown and described will be readily understood by persons familiar with the art, and when the outer ends of the hammers or beaters have worn away and it is desired to move said hammers or beaters outward, the wedge key 14 is withdrawn from the shaft 5, thus permitting the collar 12 to be moved upon the key 11, thus disengaging the clutch face 13 from the clutch face 10. The head 9 on the sleeve 7 is now engaged with a suitable tool, and said sleeve is partially rotated upon the shaft 5, which action partially rotates the disks 15 carried by said sleeve, and consequently changes the positions of the slots 16 relative the slots 20 in the disks 17. A suitable tool, such as a socket wrench, may be used on the collar 12 to hold it in the shaft 5 while the head 9 and sleeve may be held by the socket wrench while the shaft is rotated, but usually, on account of the belt connection, the shaft remains stationary while the sleeve is rotated. Thus the point of intersection between the sets of slots and which are occupied by the bolts or rods 21 are shifted radially and outwardly, thus moving the outer ends of the

hammers closer to the grinding surface or cage of the pulverizer. The collar 12 is now positioned so that the clutch face 13 re-engages the clutch face 10, and the key 14 is now seated in the shaft 5 between the collar 12 to lock the various parts in their adjusted positions. Thus it will be seen how I have constructed a simple, inexpensive pulverizer, and provided the same with simple means whereby the hammers can be adjusted radially with respect to the pulverizer shaft in order to compensate for the wear on the outer ends of said hammers.

I am aware that minor changes in the construction, arrangement and combination of the several parts of the pulverizer can be made and substituted for those herein shown and described, without in the least departing from the nature and spirit of my invention.

I claim:

In a rotary hammer mill a shaft, disks arranged on the shaft, hammers outwardly adjustably mounted in the disks, means for effecting outward adjustment of said hammers and locking means arranged directly on said shaft and co-operating with said adjusting means whereby the latter may be rigidly held in different adjusted positions.

In testimony whereof I hereunto affix my signature in the presence of two witnesses, this 28th day of November 1910.

FREDERICK R. CORNWALL.
